UNITED STATES PATENT OFFICE

HARRY C. LITTLE, OF SAN RAFAEL, CALIFORNIA

DESIGN FOR A BURNER HOUSING

Application filed January 16, 1931. Serial No. 38,326. Term of patent 3½ years.

To all whom it may concern:

Be it known that I, HARRY C. LITTLE, a citizen of the United States of America, residing at San Rafael, in the county of Marin and State of California, have invented a new, original, and ornamental Design for Burner Housings, of which the following is a specification, reference being had to the accompanying drawing, forming a part thereof.

The figure is a perspective view of the article showing my new design.

I claim:

The ornamental design for a burner housing, substantially as shown.
